UNITED STATES PATENT OFFICE

DICK J. DE PREE, OF ZEELAND, MICHIGAN, ASSIGNOR TO HERMAN MILLER CLOCK COMPANY, OF ZEELAND, MICHIGAN, A CORPORATION OF MICHIGAN

DESIGN FOR A CLOCK CASE

Application filed July 20, 1931. Serial No. 40,601. Term of patent 3½ years.

To all whom it may concern:

Be it known that I, DICK J. DE PREE, a citizen of the United States, residing at the city of Zeeland, in the county of Ottawa and State of Michigan, have invented a new, original, and ornamental Design for a Clock Case of which the following is a specification, reference being had to the accompanying drawing, forming a part thereof.

The figure is a front perspective view of a clock case showing my new design. The marks on the front face thereof above the lower border indicate surface shading.

I claim:

The ornamental design for a clock case, as shown and described.

DICK J. DE PREE.
